(57) **CLAIM**

The ornamental design for a butter storage box as shown and described.

DESCRIPTION

FIG. 1 is a top perspective view of a butter storage box showing our new design.

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a bottom perspective view thereof;

FIG. 9 is a top perspective view thereof, showing the butter storage box in an open state of use; and,

FIG. 10 is a perspective view of the butter storage box where a cover is separated from a body.

The broken lines in the drawings depict portions of the butter storage box that form no part of the claimed design.

1 Claim, 10 Drawing Sheets
